FREDERICK M. FURBER, OF REVERE, MASSACHUSETTS, ASSIGNOR TO UNITED SHOE MACHINERY COMPANY, OF PATERSON, NEW JERSEY, A CORPORATION OF NEW JERSEY.

GRINDING-MACHINE.

1,189,247.

Specification of Letters Patent.

Patented July 4, 1916.

Application filed February 21, 1913. Serial No. 749,905.

To all whom it may concern:

Be it known that I, FREDERICK M. FURBER, a citizen of the United States, residing at Revere, in the county of Suffolk and 5 State of Massachusetts, have invented certain Improvements in Grinding Machines, of which the following description, in connection with the accompanying drawings, is a specification, like reference characters 10 on the drawings indicating like parts in the several figures.

This invention relates in general to grinding machines, and especially, although not exclusively, to machines of this class designed to operate upon metallic surfaces. In such machines it is usually advantageous 15 and frequently necessary to supply a fluid such as water in order to facilitate the grinding operation and prevent the metal 20 from becoming unduly heated in the process of grinding.

The object of the present invention is to provide means for this purpose which shall be simple in construction and reliable in 25 operation and which will deliver an adequate supply of the fluid uniformly to all portions of the active surface of the grinding member.

To this end one feature of the invention 30 comprises means in a rotary grinder arranged to deliver a fluid upon the face of the grinding wheel in such manner that the fluid is caused to spread by centrifugal action uniformly toward all portions of the 35 edge of the wheel, such means preferably comprising a rotary distributer arranged to receive the fluid and deliver it centrifugally to the wheel.

A further feature resides in means where- 40 by the fluid is conveyed from a suitable source of supply, such means comprising an endless flexible carrier, such as an endless chain, arranged to convey the fluid to a convenient point for delivery to the grinding 45 wheel.

Other and more particular features of the invention will be noted in the following detailed description and pointed out in the claims.

50 The invention is illustrated as applied to a grinder having a small rapidly rotating emery wheel and designed particularly for grinding the teeth of rotary cutters; but

it should be understood that while the invention is of great practical utility as applied to such a machine, it is by no means limited thereto, but is of wide application to various types of machines of the general class indicated.

In the drawings; Figure 1 is a perspective view of a grinding machine embodying my invention; and Fig. 2 is a detail sectional view of the grinding wheel and the parts adjacent thereto.

In the machine illustrated the base 2 supports bearings 4 for the rotary shaft 6 upon one end of which is secured a grinding wheel 8. This wheel has a concave inner face presenting, in the form shown, a surface which slopes outwardly in a radial 70 curve toward the periphery of the wheel, and is designed particularly for grinding the teeth of rotary cutters. Projecting from the frame of the machine is a bracket 10 provided with a spindle 12 upon which the 75 cutter head is to be mounted while being ground. These parts are of well-known construction and require no further description.

For supplying a fluid to the grinding 80 wheel I have provided means which includes preferably a member 14 arranged to rotate with the wheel and conveniently secured as a sleeve upon the shaft, said member having at one end a diametrical enlargement and at the other end a portion 18 frusto-conical in form and of greater diameter than said enlargement and arranged closely adjacent to the concave face of the wheel, but preferably slightly spaced therefrom, as shown, so as to permit wheels of varying thickness to be mounted on the shaft without disturbing the position of the sleeve 14. The intermediate cylindrical 85 portion 16 of the sleeve is arranged to receive upon its surface the fluid that is supplied thereto in a manner to be described.

As the shaft is rotated this fluid will flow outwardly by centrifugal action over the surface of the member 18, which acts as a 90 distributor and delivers the fluid from its outer edge simultaneously at all sides upon the lateral surface or face of the wheel and practically at all points of a circle concentric with the wheel axis. The fluid will 95 then flow centrifugally outward over the 100

105

sloping surface of the grinding wheel and uniformly in all directions from the axis. Since the distributor 18 is of greater diameter than the enlargement at the other end 5 of the sleeve, the fluid will tend to flow from the cylinder 16 over the distributor rather than in the opposite direction over the enlarged end of the sleeve and will thus be utilized without waste and prevented from 10 working back along the shaft toward the bearings.

As a means for supplying fluid to the receiving member 16 I have provided beneath the shaft a receptacle 20 for a suitable cooling fluid such as water, and an endless flexible member 22 depending from the member 16 and arranged to dip within the fluid in the receptacle. In the illustrated preferred embodiment the member 22 is in the form 15 of an endless chain, but any suitable member of similar character may be employed. It will be understood that the chain 22 is driven continuously around the shaft by friction on the member 16 at a speed proportional to the speed of rotation of the shaft. The chain will thus convey the fluid that adheres thereto in its passage through the receptacle to the surface of the cylinder 25 16 where it will be taken up by the distributor 18 and delivered to the grinding wheel.

The operation of the device will be clear from the preceding description. It will be seen that the chain 22 and the distributor constitute a fluid supplying means which 30 becomes effective immediately on starting the rotation of the grinding wheel and which provides a continuous supply of fluid, the volume of which will vary in direct proportion to the speed of rotation of the wheel. Since the fluid is delivered to the wheel constantly in equal quantities upon all sides of the axis and at equal distances from the center, it will be clear that there will be no tendency for the 35 wheel to throw off the fluid at some portion of the circumference because of an unduly large supply at that point, but that the supply upon all portions of the grinding surface equidistant from the axis will be uniform.

While I have shown as a feature of the preferred arrangement a cylindrical member 16 upon the shaft which serves as a driving means for the chain and receives 40 primarily the fluid conveyed by the latter, it will be understood that the chain may be otherwise arranged to convey fluid to the distributor. It will also be understood that the position of the receptacle 20 and the 45 length and character of the member 22 may be varied according to the volume of fluid supply desired, or in view of other special considerations, and that any suitable fluid may be used with the device. Other variations also from the specific features of the

illustrated preferred embodiment are comprehended in the invention as set forth in the appended claims.

Having described my invention, what I claim as new and desire to secure by Letters Patent of the United States is the following:

1. In a machine of the class described, the combination with a grinding wheel, of means for supplying a fluid to the wheel, 75 said means being constructed and arranged to deliver the fluid upon the lateral surface of the wheel simultaneously on all sides of the wheel axis in position to flow centrifugally over said surface to the outer 80 edge of the wheel.

2. In a machine of the class described, the combination with a grinding wheel, of means for supplying a fluid to the wheel, 85 said means comprising a circular distributor constructed and arranged to deliver the fluid from all points on its peripheral edge upon the lateral surface of the wheel.

3. A machine of the class described having, in combination, a shaft, a grinding 90 wheel thereon, and a rotary distributor arranged to deliver a fluid by centrifugal action upon the lateral surface of the wheel in position to flow centrifugally over said surface to the outer edge of the wheel. 95

4. In a machine of the class described, the combination with a shaft and a grinding wheel thereon, of a frusto-conical distributor mounted on the shaft and arranged to deliver a fluid centrifugally from all points 100 on its peripheral edge upon the lateral surface of the grinding wheel, and means to supply fluid to said distributor.

5. A machine of the class described having, in combination, a shaft, a grinding 105 wheel thereon formed with a concave radially curved lateral face, a fluid distributor mounted on the shaft and arranged to deliver a fluid centrifugally upon said face, and means to supply fluid to said distributor. 110

6. A machine of the class described having, in combination, a shaft, a grinding wheel thereon formed with a concave radially curved lateral face, a frusto-conical 115 fluid distributor arranged to rotate adjacent to said face and spaced therefrom, said distributor having its end of larger diameter positioned within the concavity of said face and means to supply a fluid to said distributor. 120

7. In a machine of the class described, the combination with a shaft and a grinding wheel thereon, of a fluid receiving member mounted on said shaft means to supply 125 a fluid to said member, and a distributor arranged to receive the fluid from said member and deliver said fluid by centrifugal action upon the lateral surface of the grinding wheel in position to flow centrif- 130

- ugally over said surface to the periphery of the wheel.
8. In a machine of the class described, the combination with a grinding wheel, of a fluid receiving member arranged to rotate concentrically with said wheel, said member having a diametrical enlargement at one end and at the other end a distributor arranged to deliver a fluid by centrifugal action upon the grinding wheel, said distributor being of greater diameter than said enlargement, and means for supplying said fluid primarily to the intermediate portion of said member.
- 15 9. In a machine of the class described, the combination with a shaft and a grinding wheel thereon, of a receptacle for fluid, an endless flexible member driven by said shaft and arranged to convey the fluid from 20 said receptacle, and means to deliver the fluid from said member to the grinding wheel.
10. In a machine of the class described, the combination with a shaft and a grinding wheel thereon, of a receptacle for fluid below the shaft, an endless flexible member depending from the shaft and driven thereby, said member being arranged to dip within the fluid in said receptacle and act 30 as a carrier therefor, and means to deliver the fluid from said member to the grinding wheel.
11. In a machine of the class described, the combination with a shaft and a grinding wheel thereon, of a receptacle for fluid below the shaft, an endless chain depending from the shaft and driven thereby, said chain being arranged to dip within the fluid in said receptacle and act as a carrier 40 therefor, and a frusto-conical distributor on the shaft arranged to receive the fluid from said chain and deliver it centrifugally to the grinding wheel.
12. A machine of the class described having, in combination, a grinding wheel formed with a concave lateral face sloping outward toward the periphery of the wheel, and a rotary distributor constructed and arranged to deliver a fluid centrifugally upon said face and having its delivery portion located within the concavity of the face.
13. In a machine of the class described, the combination with a shaft and a grinding wheel thereon, of a distributor on the shaft arranged to deliver fluid by centrifugal action upon the surface of the wheel, and an endless flexible member driven by the shaft and arranged to convey fluid to 60 said distributor.
14. A machine of the class described having, in combination, a grinding wheel recessed at one side to provide a lateral face that slopes relatively to the axis toward the periphery of the wheel, a fluid distributor having a substantially circular outer edge within said lateral recess of the grinding wheel in position to deliver fluid upon 65 said face uniformly around the axis of the wheel, and means for supplying fluid to said 70 distributor.
15. A machine of the class described having, in combination, a grinding wheel recessed at one side to provide a lateral face that slopes relatively to the axis toward the 75 periphery of the wheel, a frusto-conical fluid distributor having its end of larger diameter adjacent to said face in position to deliver fluid upon said face uniformly around the axis of the wheel, and means 80 for supplying fluid to said distributor.
16. A machine of the class described having, in combination, a grinding wheel recessed at one side to provide a lateral face that slopes relatively to the axis toward the 85 periphery of the wheel, a rotary fluid distributor constructed and arranged to deliver fluid by centrifugal action upon said face uniformly around the axis of the wheel, and means for supplying fluid to said 90 distributor.
- In testimony whereof I have signed my name to this specification in the presence of two subscribing witnesses.
